CYLINDER HONING

Victor W. Peterson, Chicago, Ill., assignor to
Hannifin Corporation, a corporation of Illinois

Application February 17, 1944, Serial No. 522,690

5 Claims. (Cl. 51—184.3)

1

This invention relates to honing of cylinders and the like, and among other objects aims to improve the efficiency and quality of honing operations.

The nature of the invention may be readily understood by reference to one illustrative embodiment thereof described in the following specification and illustrated in the accompanying drawings.

In said drawings:

Fig. 1 is an elevation, diagrammatic in character, of a hone operating and controlling apparatus;

Fig. 2 is a vertical section through the hone pressure applying and controlling device;

Fig. 3 is an elevation partly in section on the plane 3—3 of Fig. 4 of a detail of the pressure applying apparatus;

Fig. 4 is a plan section taken on the plane 4—4 of Figs. 2 and 3;

Fig. 5 is a sectional elevation of a detail taken on the plane 5—5 of Fig. 4;

Fig. 6 is a longitudinal section of a honing head;

Fig. 7 is a cross view partly in section on the plane 7—7 of Fig. 6 showing details of the honing head, and

Fig. 8 is a view showing devices for adapting the honing head to different bore diameters.

Honing, as applied to cylinders, such as cylindrical bores, is designed not only to provide surface finish but to provide a true and uniform bore. Heretofore it has been possible by means of honing to finish relatively short cylinders, such as engine cylinders, with satisfactory accuracy; this has not been true of cylinders which are many times longer than the honing tool itself. For example, in long cylinders the honing stone wear (which is essential to maintain an efficient cutting surface) in a single stroke of the hone is sufficient to result in a measurably smaller bore at the far end of the cylinder than at the near end. In the commercial type of hone, it is not customary nor indeed practicable to make an adjustment of the honing tool during a given stroke to compensate for stone wear. Adjustment is generally made at the end of a stroke when the honing head is at the entering (or near) end of the cylinder. If the adjustment of stone pressure be too great there will be excessive stone pressure often resulting in stone breakage and consequent loss of honing efficiency. It is important for honing efficiency that stone pressure be maintained at its proper value throughout the length of the bore, but it is equally important to

2

control the stone pressure to avoid excessive pressure while maintaining a pressure sufficiently high for efficient cutting.

According to the present invention, the stone pressure is under instant and sensitive control of the operator at all points throughout the bore, and particularly the stone pressure may be reduced or increased during a single stroke to adjust the stone pressure to the proper value. If

10 the stone pressure be excessive as evidenced by a gauge or by the particular sound which the stones make the bore, the operator may immediately reduce pressure until proper honing conditions are restored. Similarly if the stone pressure be inadequate as evidenced by a gauge or by the sound of the stone in the bore, the operator may sensitively increase such pressure to the proper value and continue such adjustments intermediate the ends of the stroke at all stages of the honing operations. If the operator be provided with means for instantaneously adjusting stone pressure at any point in the stroke, the sound or "squeal" made by the stones in cutting affords a means for regulating the stone pressure. With 15 little practice the operator can tell by the pitch of the squeal whether the pressure be too high, too low or the correct pressure.

In the present instance pressure is transmitted to the honing stones hydraulically by means of 20 a manually controlled (in this case manually operated) pressure supply device, thereby making it possible to effect slight changes in the pressure. This is not possible with a mechanical pressure applying means, since there is no means 25 for determining the degree of adjustment in pressure changes made by a given mechanical adjustment.

In the drawings (Fig. 1) one form of hone operating apparatus is shown diagrammatically for 30 purposes of illustration. The invention is not limited to any particular operating apparatus. In the present case the honing head 10 carrying a plurality of honing stones 11 is reciprocated and, if desired, rotated or oscillated by a spindle 35 12 to which it is connected by a universal joint 13 of conventional design. The spindle 12 is reciprocated by a double acting cylinder and piston 14, the details of which it is not necessary here to describe. Rotation or oscillation of the spindle 15 (and the honing head) is effected, if desired, by the mechanism 16 through which the spindle 12 (which is non-circular in section, e. g., square) slides.

Extending longitudinally of the spindle 12 and 40 preferably lying in a groove in or inside the

spindle, is a hydraulic line 16 which conveys hydraulic pressure to the hone and presses the hone stones outwardly by appropriate means, one such means being presently described. The remote end of the oscillatable spindle 12 is carried in a non-rotatable cross-head 17 which slides along the guides 18 on the bed of the apparatus and provides a thrust bearing for reciprocating the spindle. The operating piston rod 19 is connected to the cross-head by means of a bracket 20 on which the pressure supply means 21 may advantageously be mounted. The cross-head 17 also carries a hydraulic coupling or rotary fitting 22 connecting the line 16 (which oscillates with the spindle 12) with the non-oscillating line 23 leading to the pressure applying device 21. Any suitable rotary fluid coupling may be employed for this purpose.

The hydraulic pressure applying means 21 (Fig. 2) comprises a cylinder 25 and piston 26, together with pressure generating means in the form of a manually operated pump 27 (Fig. 3). The latter is operated manually to force hydraulic fluid such as oil from the reservoir 28 through passage 29 into cylinder 25 thereby displacing piston 26 and delivering pressure to line 16 connected to the cylinder through passage 30. Pressure accumulating means are advantageously provided for accumulating pressure fluid and also, in this instance, for gradually increasing the pressure to the desired degree. Such accumulating means are here shown in the form of a relatively heavy spring 33 located within a cylindrical housing 34, constituting an extension of cylinder 25, and bearing against piston 26. Initial spring pressure is adjusted by a screw plug 35 in the end of the cylinder and against which the other end of the spring bears.

To apply pressure to the honing head and thence to the honing stones, the operator simply operates the pump 27, in this instance by reciprocating pump handle 36 until pressure develops to the desired degree. This results in a movement of the piston 26 and compression of spring 33. The degree of hydraulic pressure is indicated by pressure gauge 37 advantageously in line 23, but the operator also utilizes the sound made by the honing stones to determine whether in each case an efficient honing pressure is being applied. The accumulated pressure applied by spring 33 to piston 26 maintains the pressure substantially constant for an appreciable period of time to compensate or take up for stone wear. Since the hydraulic fluid is substantially incompressible, the volume of fluid displaced to develop the necessary pressure and also to vary the pressure is, of course, relatively small and requires only a small pump and relatively few strokes of the pump. If the pressure be too high in a given case, it may be immediately reduced by the operator by opening valve 38. Opening of the valve allows fluid to pass from the cylinder through passage 39 into passage 40 and reservoir 28. Preferably valve 38 is a needle valve which permits a very restricted opening for return of fluid to prevent a sudden drop in hydraulic and stone pressure. As soon as the pressure has dropped to the desired degree as indicated by the gauge 37 or by the sound of the stones, the operator immediately closes valve 38. The latter is provided with an operating handle 41.

An indicator in the form of a rod 42 connected to piston 26 and extending through a bore in the threaded plug 35 indicates the degree of compression of spring 33 and particularly indicates

the volume of pressure fluid in the accumulator to apprise the operator when an additional supply is necessary.

Pump 27 comprises a small plunger 46 carrying a seal or packing 47 at its end and passing through a stuffing box 48 to a pivoted connection 49 with the operating mechanism. The latter comprises a lever 50 pivoted at 51 and carrying the operating handle 36. In operation of the pump hydraulic fluid is drawn from reservoir 28 through passage 52 into the pump cylinder 53 from which it is expelled by the piston through the passage 54 and thence into the main cylinder 25 through passage 29. The passages 52 and 54 are provided with check valves 55 and 56 respectively to prevent flow in the reverse direction.

To protect the honing head against the inadvertent or accidental application of excessive pressure, a relief valve 57 (Fig. 5) is advantageously connected with cylinder 25 through passages 58 and 30. As here shown (Fig. 5), the relief valve comprises a ball valve 59 pressed against its seat by a spring 60 whose pressure is adjusted by screw plug 61. Adjustment of the relief valve is made by removing the reservoir filling plug 62 and inserting a tool through the opening thereby provided. The filling plug 62 carries a vent 63 with a check valve 64.

The line 16 which conducts pressure to the honing head is bent around the universal joint 63 and enters the honing head at 67. The tube comprising the line 16 is sufficiently flexible to accommodate the slight movements which may occur in the universal joint.

The operating mechanism is not limited in its use to a specific form of honing head. The one here illustrated is a substantial improvement over known types and in addition is simple and inexpensive in construction. The present honing head (Figs. 6-8) comprises a hydraulic cylinder 68 carrying a piston 69 operated by pressure fluid entering the cylinder. The movement of the piston is in this instance communicated to the honing stones 11 by mechanism in the form of wedges or cams 70 which bear against cam surfaces 71 on the carrier 72 for the honing stones. The longitudinal thrust of the wedges on the stone carriers is carried by pins 73 flattened adjacent their ends, passing through the carriers 72 and seated in the slots 74 in the hone housing 75 (Figs. 6 and 7). The stone carriers each are provided with a groove 76 in which the stone elements seat. These are held in position by appropriate means such as the conventional garter springs 77 which bear against the extending hooks 78 on the metal clips 79 embracing the base of the stones.

Inward movement of the stones is effected in this instance by a spring 80 which returns piston 69 (upon reduction of hydraulic pressure) thereby relatively shifting the cam surfaces 79 and 71 and allowing the garter spring 77 to pull the stones inwardly.

The honing head may advantageously be provided with a device which limits the outward movement of the stones by limiting the advance of the piston. Such means is here shown in the form of an adjustable stop 81 whose end 82 is adapted to be engaged by and arrest further movement of the piston. The stop 81 is threaded at its extremity 83 in a sleeve 84 carried by the honing head and may be adjusted longitudinally to adjust the position of its end 82 by means of a key 85.

The hone may be adapted for use in bores of

larger diameter by the use of inserts 39 of various depth (see Fig. 8). The insert bases are shouldered at 90 to seat in the grooves 76 in carriers 72 and are held therein by screws passing through the holes 91 in the base of the inserts and screwed into threaded holes 92 in the carriers 72. Like the carriers the inserts are provided with stone receiving grooves 93.

In operation, the hone and pressure applying mechanism reciprocates sufficiently slowly to permit the operator to make the necessary manipulations while in motion.

In operation, it is apparent that honing stone pressure is under the sensitive control of the operator at all stages of the honing cycle.

Obviously the invention is not limited to the details of the illustrative apparatus since these may be variously modified. Moreover, it is not indispensable that all features of the invention be used conjointly since various features may be used to advantage in different combinations and subcombinations.

Having described my invention, I claim:

1. Honing apparatus comprising in combination a hydraulically expansible honing head including a hydraulically actuated cylinder for controlling honing pressure, a reciprocating cross-head and an elongated spindle carried thereby for operating said honing head, a hydraulic line carried by said spindle for conducting hydraulic pressure to said honing head cylinder, means connected with said cross-head for reciprocating said spindle and honing head, means including a small manually operated hydraulic pump and a low capacity accumulator therefor carried on and reciprocating with said cross-head for sensitively increasing and decreasing hydraulic pressure to said cylinder during operation of the hone to control the honing pressure, and a rotary hydraulic connection at the cross-head end of said spindle for connecting said accumulator with said line for transmitting pressure from said accumulator to said line.

2. A honing head comprising in combination a cylindrical body, a plurality of radially movable honing stones around said body, a hydraulic cylinder in said body having a longitudinally movable piston therein, said body having a connection for delivering pressure fluid to said cylinder, means for transmitting radial force from said longitudinally movable piston to said honing stones for moving the latter radially outwardly, and a stop rod extending longitudinally through said body and adapted to engage said piston to limit its forward movement, said rod being threaded into the end of said body opposite said piston and having means on the exterior of said body for rotating said rod to vary the limits of movement of said piston.

3. In honing apparatus the combination comprising a honing head having means actuated by hydraulic pressure for variably increasing and decreasing honing pressure, means for applying hydraulic pressure to said head to control the honing pressure including a low capacity accumulator wherein the pressure is quickly changeable, a liquid reservoir, a hydraulic line leading from said accumulator to said honing head to operate said hydraulically actuated means, said accumulator having elastic means for yieldably sustaining hydraulic pressure, said pressure varying with the volume of liquid in said accumulator, and means effective during operation of

the hone for sensitively increasing and decreasing at will the volume of liquid in said accumulator to increase and decrease honing pressure comprising a manually operated pump, a passage connecting the inlet of the pump to the reservoir, a passage connecting the outlet of the pump to the accumulator, a passage connecting the reservoir and the accumulator, and a manually operated valve in the last named passage for bleeding liquid from the accumulator into the reservoir.

4. In honing apparatus including mechanism for reciprocating and oscillating a honing head, the combination comprising a honing head having hydraulically actuated means responsive to hydraulic pressure for variably increasing and decreasing honing pressure, means for applying hydraulic pressure to said head to control the honing pressure including a low capacity variable pressure accumulator cylinder whose pressure varies substantially with the volume of liquid therein and having spring means for yieldably sustaining hydraulic pressure of the liquid, a hydraulic line connecting said accumulator cylinder with said honing head, a small capacity manually operated hydraulic pump effective during operation of the hone connected to the accumulator cylinder for increasing manually at will the volume of liquid therein, and a manually operated valve connected with the accumulator cylinder for decreasing manually at will the volume of liquid therein.

5. Honing apparatus comprising in combination a honing head having therein means including a hydraulic cylinder for variably increasing and decreasing honing pressure, head reciprocating and oscillating mechanism, a variable pressure accumulator carried by and reciprocating with said mechanism and being of such low capacity that its pressure varies substantially with the volume of liquid therein, a hydraulic line connecting said accumulator with said cylinder and having a rotatable hydraulic coupling to convey liquid pressure to the head oscillating mechanism, resilient means for yieldably sustaining liquid pressure in said cylinder, and manually operated means for sensitively increasing and decreasing the accumulator pressure at will during operation of the hone to control the honing pressure, said last named means comprising a manually operated pump connected to the accumulator for increasing the volume of liquid therein and a manually operated valve for decreasing the volume of liquid therein.
